UNITED STATES PATENT OFFICE

ALLEN W. CLARKE, OF RIDGEWOOD, NEW JERSEY, ASSIGNOR TO AMERICAN CAR AND FOUNDRY COMPANY, OF NEW YORK, N. Y., A CORPORATION OF NEW JERSEY

ARTICULATED CAR

Application filed November 1, 1930. Serial No. 492,688.

This invention relates to articulated cars of the type in which the adjacent end portions of two car bodies are supported by a single truck known in the art as a pivot truck.

One object of this invention is the provision of a connection for the adjacent end portions of adjacent bodies of an articulated car which will maintain the ends in their proper relative positions and at the same time permit the bodies to turn or pivot relative to each other when rounding curves.

Another object of this invention is the provision of a connection for the adjacent end portions of adjacent bodies of an articulated car which includes a pivot truck having spaced independently functioning bolsters for respectively supporting the adjacent end portions of said bodies; the truck also including an element into which the car ends extend for preventing relative lateral shifting of the bodies and for transmitting traction stresses from the bodies to the truck from one body to the other through the truck.

Still another object of this invention is the provision of a new and improved body connection casting for an articulated car.

A further object of this invention is the provision of an articulated car construction having a plurality of car bodies connected to a common truck, the adjacent ends of said bodies having interengaged body connection castings which prevent relative vertical shifting of the bodies.

Other objects and advantages of this invention will be apparent from the following description taken in conjunction with the accompanying drawings in which:

Fig. 1 is a top plan view of the end portions of adjacent car bodies, certain parts being shown in section, other parts being broken away and still other parts being omitted in order to more clearly show the invention.

Fig. 2 is a sectional view through the articulated joint.

Fig. 3 is an end view of one of the car bodies showing the body connection casting in position with truck transoms and center casting removed.

Fig. 4 is a top plan view of the body connection casting.

Fig. 5 is a sectional view on the line 5—5, Fig. 4.

Fig. 6 is a sectional view on the line 6—6, Fig. 4.

Fig. 7 is a front elevation of the body connection casting shown in Fig. 4.

Fig. 8 is a sectional view through the adjacent end portions of adjacent car bodies showing a modification of the articulated joint, and

Fig. 9 is a partial top plan view of the modification shown in Fig. 8.

Referring now more particularly to the drawings in which similar characters of reference designate similar parts in the several views, the adjacent end portions of two car bodies are shown at A and B, the bodies having an underframe which includes spaced channels 2 forming the center sills, and an end sill of any preferred or desired construction.

The adjacent ends of the car bodies are provided with doorways, framed by U-shaped channels the sides of which define posts 4; one flange of each of the channels being extended beyond its car end to define an attaching means for a flexible diaphragm 6, as shown clearly in Fig. 1, the diaphragm defining a closed passageway between the adjacent bodies A and B.

The adjacent end portions of bodies A and B are supported by a common or pivot truck indicated generally at C which is provided with a pair of independent spaced bolsters 8, one arranged under the end portion of each body as clearly shown in Fig. 2 and said bolsters are each arranged between pairs of transoms 10. Each bolster 8 is provided with a bearing 12 on its upper surface, said bearings being segmental or arcuate in shape and receiving segmental body bearings 14 which depend from the end portions of the respective car bodies. Specifically the body bearings are preferably formed integral with the bottom walls of body connection castings indicated generally at D which are secured to and form part of the body underframes, and as shown more clearly in Figs. 4 to 7, inclu-

sive, each casting comprises a body portion having top and bottom walls 16 and 18 respectively and a front wall 20 curved to the form shown in Fig. 4 to define a buffing and pivoting area 22 midway between the side walls 24 of the casting. The castings are reinforced by internal longitudinal and transverse webs 26 and 28 respectively and said castings extend between the spaced channels 2, with their side walls 24 in engagement with and secured to said channels by suitable fasteners such as the rivets 30.

The castings D are provided adjacent their front ends with depending arcuate projections 32 which extend into a transverse truck member E arranged between the bolsters 8; the member E comprising in the instance shown, the transoms 10 between the bolsters 8 and a hollow truck centering casting 34 into which the projections 32 extend. As shown clearly in Fig. 2 the casting 34 is thickened at 35 adjacent its upper end to reinforce the casting and in practice, pulling stresses are transmitted from the car bodies to the truck through the transverse member E and obviously through the casting 34. The opening in the casting 34 is substantially circular to conform to the arcuate shape of the projections 32 and it will be apparent that relative lateral shifting of the car bodies is prevented through the engagement of the projections 32 with the casting 34.

The side edges of the projections 32 are provided respectively with a vertically arranged projecting tongue 36 and a vertically arranged recess or groove 38, and the castings on adjacent end portions of adjacent cars are identical, therefore, when the bodies are assembled, the tongue 36 of one casting will enter the groove 38 of the adjacent casting, as shown more clearly in Fig. 2, and thus restrain the car bodies against relative vertical shifting; the castings D in effect being interengaged.

The castings D, just described, bear a certain resemblance to the casting D shown in application of Allen W. Clarke and William Griffin filed November 1, 1930, Serial Number 492,687 but differ from said casting in the Clarke and Griffin application in several respects as will be apparent from a comparison of the respective castings. For instance, the castings in the invention shown herein are so formed that when they are attached to the adjacent end portions of car bodies they substantially abut so that buffing stresses are transmitted directly from one car body to the other. A further distinction between the casting shown in the present invention and that of the Clarke and Griffin invention is that the projection 32 in the present invention is arranged adjacent the end of the body portion of the casting whereas in the Clarke and Griffin construction the projection is arranged at the forward end of the casting.

The arrangement of the projection on the casting of the present invention is provided so that the forward end of the casting constitutes a buffing area.

Secured to the car bodies on each side of the castings D are body side bearings 40 adapted to cooperate with truck side bearings 42, which in the instance shown are rollers though obviously the side bearings may assume any desired or preferred form.

Extending between adjacent car bodies is a foot plate 44 supported by brackets 46 of Z shape in cross section; the brackets resting upon end top cover plates 48 secured to the castings D. Clips 50 are provided which are secured to the plates 48 and overlap the lower flange of the Z shaped brackets 46 to restrain the latter, and hence the foot plate against displacement. The foot plate 44 is supported in a manner similar to that shown, described and claimed in the before mentioned Clarke and Griffin application and no claim to the specific manner of supporting a foot plate is made in this application.

Fig. 8 discloses a modification of the construction shown in the remaining figures and the body center castings shown in Fig. 8 have the body bearings 51 formed separately thereof and attached to the end surfaces by means of rivets 52 or other suitable fasteners. The modification shows the end projections and the buffing surfaces formed independently of the connection castings and this modification contemplates the provision of a separate element secured to the castings. It is possible that in practice the projections 32 and buffing and pivoting areas 22 shown in Fig. 2 will wear to such an extent that replacement is necessary. This is due to contact of the projections 32 with the thickened portion 35 of the casting 34 and contact of areas 22 with each other. To permit replacement of parts, the castings D shown in Fig. 8 are each formed with an attaching face 54 at the front end thereof which preferably is machined to nicely receive an end casting indicated generally at 56 and comprising a buffing portion 58 and an arcuate depending projection 60 having its side edges provided respectively with a tongue 62 and a groove 64. The surface 54 is arranged at substantially right angles to the side walls 24 of the casting, as clearly shown in Fig. 5, and the end casting 56 is complementary to the end of casting D, as will be apparent. The end castings 56 are each provided with a horizontally extending attaching surface 66 which underlie the lower walls of the castings D and are secured thereto by suitable fasteners such as the rivets 68.

From the above description it is believed that the construction of the car of the present invention will be fully apparent to those skilled in the art. In operation, in passing around curves, the two car bodies A and B will swivel about the abutting surfaces at

the forward ends of the castings D; said abutting ends defining a pivot. Obviously it is necessary to provide sufficient clearance between working parts to compensate for breaks in track grades and this has been done in 5 designing the car of the present invention.

As each car body is supported by its own truck bolster, bearings and side bearings, each body may oscillate or sway independently of or relative to the other. At the same time the bodies are prevented from relative vertical shifting due to the interengagement of the projections 32. The interengagement of the projections 32 in effect constitutes an interengagement of the castings D and said interengagement serves also to distribute excess load on one car to the other through the tongue and groove connections to the other body and then to the bolster and truck.

20 The castings D having their forward ends in abutting relation serve to retain the bodies in proper spaced relation and also serve to take up buffing shocks to which the bodies are subjected. The projections 32 extend into the transverse truck member E and pulling stresses between said bodies are transmitted from the bodies to the truck and to each other through said member E as will be apparent; this in addition to the usual 25 transmission of pulling stresses through the connected body and truck bearings.

It will be apparent from the above description that an articulated joint for railway vehicles has been provided which will permit 30 the necessary turning of adjacent car bodies, but which will prevent the separation of adjacent bodies in the event of failure of the segmental connections between the respective bodies and truck bolsters; the transverse member E serving to hold said bodies together.

40 The drawings show one embodiment of the invention but it is to be understood that they are for illustrative purposes only and various 45 changes in the form and proportions of the construction may be made within the spirit of the invention without departing from the scope of the appended claims.

What is claimed is:

50 1. In an articulated car, a plurality of car bodies, a truck for supporting the adjacent end portions of said bodies, a pair of spaced bolsters carried by the truck, body connection castings secured to the bodies at their adjacent end portions and arranged in substantially abutting relation, said castings each having a body center bearing in engagement with one of said bolsters.

55 2. In an articulated car, a plurality of car bodies, a truck for supporting the adjacent end portions of said bodies, said truck having a pair of independent bolsters by which the car bodies are respectively supported, body connection castings secured to the adjacent end portions of said bodies and arranged in

substantially abutting relation, a truck center casting, and projections depending from the body connection castings extended into the truck center casting.

3. In an articulated car, a plurality of car bodies, a truck for supporting the adjacent end portions of said bodies, said truck having a pair of independent bolsters by which the car bodies are respectively supported, body connection castings secured to the adjacent 75 end portions of said bodies and arranged in substantially abutting relation, a truck center casting intermediate the bolsters, and projections depending from the body connection castings extended into the truck center 80 casting.

4. In an articulated car, a pair of car bodies arranged end to end in substantially abutting relation, a truck for supporting the adjacent end portions of said bodies, and means for connecting said bodies and truck comprising a pivot between said end portions, a pair of bolsters each arranged beneath one end portion of one of said bodies, and interengaged 85 body and truck bearings between said end portions and bolsters adapted to permit horizontal swiveling movement of the bodies in a confined path, said pivot being the center of 90 swiveling movement.

5. In an articulated car, a pair of car bodies arranged end to end in substantially abutting relation, a truck for supporting the adjacent end portions of said bodies, and means for connecting said bodies and truck comprising a pivot between said end portions, a pair of 95 bolsters each arranged beneath one end portion of one of said bodies, bearings between said end portions and bolsters adapted to permit horizontal rotation of the car ends, 100 said pivot being the center of rotation, and interengaging projections on the car end portions 105 for preventing relative vertical shifting of said end portions.

6. In an articulated car, a pair of car bodies arranged end to end in substantially abutting relation, a truck for supporting the adjacent end portions of said bodies, and means for connecting said bodies and truck comprising a pivot between said ends, a truck bolster arranged beneath the end portion of each car body, bearings between the end portions and their respective bolsters adapted to permit horizontal rotation of said end portions, 110 said pivot being the center of rotation and comprising a truck center casting and projections on said car ends extending into the truck center casting and cooperating therewith for transmitting pulling stresses from the bodies to the truck and for preventing 115 relative horizontal shifting of the car bodies.

7. In an articulated car, a pair of car bodies arranged end to end in substantially abutting relation, a truck for supporting the adjacent end portions of said bodies, and means for connecting said bodies and truck comprising 120 125

- a pivot between said ends, a truck bolster arranged beneath the end portion of each car body, bearings between the end portions and their respective bolsters adapted to permit horizontal rotation of said end portions, said pivot being the center of rotation and comprising a truck center casting arranged between said bolsters and projections on said car ends extending into the truck center casting and cooperating therewith for transmitting pulling stresses from the bodies to the truck and for preventing relative horizontal shifting of the car bodies.
8. In an articulated car, a pair of car bodies arranged end to end in substantially abutting relation, a truck for supporting the adjacent end portions of said bodies, and means for connecting said bodies and truck comprising a pivot between said ends, a truck bolster arranged beneath the end portion of each car body, bearings between the end portions and their respective bolsters adapted to permit horizontal rotation of said end portions, said pivot being the center of rotation and comprising a truck center casting arranged between said bolsters and projections on said car ends extending into the truck center casting and cooperating therewith for transmitting pulling stresses from the bodies to the truck and for preventing relative horizontal shifting of the car bodies, said projections being interengaged whereby to prevent relative vertical shifting of the car bodies.
9. In an articulated car comprising a plurality of car bodies, underframes for said bodies, body connection castings secured to adjacent end portions of said bodies and provided with bearing elements depending therefrom intermediate the ends thereof, said castings being provided with curved forward ends defining buffing areas arranged in substantially abutting relation, a projection on one of said ends, the other of said ends having a recess adapted to receive said projection to prevent relative vertical shifting of the bodies.
10. In an articulated car, a plurality of car bodies arranged end to end to transmit buffing shocks directly from one to the other, a truck supporting the adjacent end portions of said bodies, a plurality of independently functioning truck bearings on the truck, a body bearing on each of said end portions adapted to cooperate respectively with the truck bearings to permit horizontal swiveling movement between said bodies and truck, and a projection on one of said end portions engaging the other of said end portions to prevent excessive relative vertical shifting of the bodies.
11. In an articulated car comprising a plurality of car bodies, a truck supporting the adjacent ends of two of said bodies, a plurality of independently functioning truck bearings on the truck, a body bearing on each of said end portions adapted to cooperate respectively with the truck bearings to permit horizontal swiveling movement between said bodies and truck, and a projection on one of said end portions engaging the other of said end portions to prevent excessive relative vertical shifting of the bodies.
12. In an articulated car comprising a plurality of car bodies the adjacent end portions of which are arranged in abutting relation whereby to transmit buffing shocks from one body to the other, a truck supporting the adjacent end portions of said bodies, a pair of bearing plates on the truck, bearing members on the bodies cooperating respectively with the truck bearing members, and projections depending from the adjacent end portions of the bodies intermediate the connected body and truck bearings and cooperating with a truck part for preventing sidewise shifting of the bodies and for transmitting pulling stresses from the bodies to the truck.
13. In an articulated car comprising a plurality of car bodies the adjacent end portions of which are arranged in abutting relation, a truck supporting the adjacent end portions of said bodies, a pair of bearing plates on the truck, bearing members on the bodies cooperating respectively with the truck bearing members, and projections depending from the adjacent end portions of the bodies intermediate the connected body and truck bearings and cooperating with a truck part for preventing relative sidewise shifting of the bodies and for transmitting pulling stresses from the bodies to the truck, said projections being interengaged to prevent excessive relative vertical shifting of the bodies.
14. In an articulated car comprising a pair of car bodies, abutting connection castings secured to the adjacent end portions of said bodies and provided with depending bearings and with depending projections, said projections being arranged adjacent the forward ends of said castings, a truck beneath the adjacent end portions of said bodies with which said body bearings are engaged for swiveling movement, and a transverse member carried by the truck into which the projections extend whereby relative lateral shifting of the bodies is prevented and pulling stresses are transmitted from the bodies to the truck.
15. A body connection casting for articulated cars comprising a hollow body provided with a buffing surface and a depending projection adjacent its forward end, and with a body bearing depending from the bottom of the casting at a point remote from the forward end of said casting.
16. A body connection casting for articulated cars comprising a body portion, a buffing casting attached to the forward end of said body portion and provided with a de-

pending projection, and a body bearing detachably secured to and depending from the bottom of the body portion at a point remote from said projection, said body bearing being longitudinally alined with said projection.

17. In an articulated car, a pair of car bodies arranged end to end in substantially abutting relation, a truck for supporting the adjacent end portions of said bodies and means for connecting said bodies and truck comprising a pivot between said ends, a truck bolster arranged beneath the end portion of each car body, bearings between the end portions and their respective bolsters adapted to permit horizontal rotation of said end portions, said pivot being the center of rotation, a truck center casting arranged between said bolsters, and projections on said car ends extending into the truck center casting and cooperating therewith for transmitting pulling stresses from the bodies to the truck and from one body to the other and for preventing relative horizontal shifting of the car bodies.

18. In an articulated car, a plurality of car bodies, a truck for supporting the adjacent end portions of said bodies, a pair of spaced bolsters carried by the truck, bearings between the end portions and their respective bolsters adapted to permit horizontal swiveling movement of the bodies, and means interconnecting the bolsters for pivotally connecting the adjacent end portions of the bodies to the truck, said adjacent end portions being arranged in substantially abutting relation above the pivot connection.

19. In an articulated car, a pair of car bodies arranged end to end in substantially abutting relation whereby buffing shocks may be transmitted directly from one body to the other, the adjacent end portions of the bodies being provided with pivot elements depending therefrom and arranged in interengaged relation and adapted to engage a truck part.

20. In an articulated car, a pair of car bodies arranged end to end and provided with buffing surfaces positioned in substantially abutting relation, the adjacent end portions being provided with vertically depending pivot elements arranged in interengaged relation to prevent excessive relative vertical shifting of the bodies and adapted to engage a truck part.

21. In an articulated car, a pair of car bodies arranged end to end and provided with horizontally alined abutting buffing surfaces for transmitting buffing shocks directly from one body to the other, and pivot elements depending from the end portions adapted to engage a truck part, said pivot elements being so formed as to be interengaged in a plane below the abutting buffing surfaces.

22. In an articulated car, a plurality of car bodies arranged end to end, a truck for supporting the adjacent end portions of said

bodies, said truck having a pair of bolsters arranged respectively beneath said bodies, bearings between the end portions and said bolsters, a transverse truck member, and projections depending from the end portions into the said truck member to pivotally connect said bodies and truck, the adjacent end portions of said bodies abutting at substantially the pivotal axis.

23. A body connection casting for articulated cars comprising a body portion adapted to be arranged longitudinally of a car underframe for attachment to the center sills of said underframe, a buffing casting attached to the forward end of said body portion and provided with a depending projection, and a body bearing secured to said body portion intermediate its ends.

24. In an articulated car, a pair of car bodies arranged end to end, a truck for supporting the bodies provided with a pair of bolsters, bearings between the end portions of said bodies and said bolsters, means on said bodies and truck in cooperative relation between the bolsters for connecting the bodies and truck to permit pivotal movement of the bodies about a vertical axis, the adjacent end portions of the bodies being arranged in substantially abutting relation in a plane above but substantially in line with the pivotal axis.

In witness whereof I have hereunto set my hand.

ALLEN W. CLARKE.
